UNITED STATES PATENT OFFICE.

HAROLD W. EDEN, OF ALTON, ILLINOIS, ASSIGNOR, BY MESNE ASSIGNMENTS, TO
GILLESPIE-EDEN CORPORATION, A CORPORATION OF DELAWARE.

WASHING-MACHINE DRIVE.

1,387,696.

Specification of Letters Patent. Patented Aug. 16, 1921.

Application filed August 13, 1917. Serial No. 185,896.

To all whom it may concern:

Be it known that I, HAROLD W. EDEN, a citizen of the United States, and a resident of town of Alton, in the county of Madison 5 and State of Illinois, have invented certain new and useful Improvements in a Washing-Machine Drive; and I do hereby declare that the following is a full, clear, and exact description of the same, reference being had 10 to the accompanying drawings, and to the numerals of reference marked thereon, which form a part of this specification.

This invention relates to an improved arrangement and construction of driving 15 mechanism for the clothes drum and wringer of a washing machine whereby either one may be operated independently of the other, and with the drive shaft for the clothes drum of the machine reversed automatically 20 during its operation. Furthermore, a releasable driving means is provided whereby, in the event of the clothes drum or wringer becoming jammed, said means will permit slippage of the parts until the power 25 can be turned off, thus protecting the mechanism from damage.

It is an object therefore of this invention to construct a driving mechanism for the parts of the washing machine embracing a 30 reversing gear mechanism for the clothes drum as well as a reversible wringer drive, and with the parts ceasing operation in the event of jamming of the wringer or clothes drum mechanisms to prevent damage to the 35 parts.

It is also an object of this invention to construct a power driven washing machine wherein the driving means are incased and mounted upon one side of the machine, and 40 entirely automatic in operation after the circuit to the driving motor is closed.

It is furthermore an important object of this invention to construct an improved and compact driving mechanism for a washing 45 machine with all the parts easily accessible, and mounted upon one side of the frame of the washing machine to impart a drive to the clothes drum or wringer of the machine alternately or simultaneously independently 50 of one another, as desired.

Other and further important objects of the invention will be apparent from the disclosure in the specification and drawings.

The invention (in a preferred form) is

illustrated in the drawings and hereinafter 55 more fully described.

On the drawings:

Figure 1 is a front view of a washing machine showing a driving mechanism embodying the principles of my invention 60 forming a part thereof and mounted on one side of the washing machine.

Fig. 2 is a side elevation of the washing machine.

Fig. 3 is a sectional detail through one of 65 the gears of the reversing gear mechanism.

Fig. 4 is a fragmentary enlarged side view of the washing machine with the casing of the driving mechanism broken away and shown in section to illustrate the arrangement of the parts.

Fig. 5 is a sectional detail taken on line 5—5 of Fig. 2, with parts omitted and parts shown in elevation.

Fig. 6 is a sectional detail taken on line 75 6—6 of Fig. 5.

Fig. 7 is a fragmentary detail section showing the main drive shaft and friction releasing clutch which are driven by the 80 motor.

Fig. 8 is a fragmentary sectional detail on line 8—8 of Fig. 2, with parts shown in elevation.

Fig. 9 is an enlarged detail view taken on line 9—9 of Fig. 7, of the releasing clutch 85 of the mechanism.

Fig. 10 is an enlarged detail view taken on line 10—10 of Fig. 8.

Fig. 11 is a sectional detail taken on line 11—11 of Fig. 7. 90

As shown on the drawings:

The reference numeral 1, indicates the frame of a washing machine having a tub 2, of usual or well known construction fitted therein, and with the driving mechanism 95 for the machine mounted on one side of the frame. Mounted upon a bracket 3, which is secured upon the frame of the machine is a driving motor 4, and the drive shaft of said motor, denoted by the reference number 5, leads into a tubular casing 6, as shown in Figs. 4 and 7. The cylindrical casing 6, is connected upon the boss extension of a large casing 7, forming a part of or secured upon the frame of the washing 100 machine and provided with an L-shaped cover plate 8, as shown in Fig. 2. Said casing 7, is provided with an inwardly pro-

jecting extension 8^a, as shown clearly in Fig. 4, affording a bearing for one end of a shaft 9, and the other end of said shaft extends through the wall of the casing 7, 5 through a bearing provided therefor, and is provided with a coupling 10, pinned thereon. Secured in the coupling 10, is a short shaft section 11, which is pinned to a long coupling shaft or member 12, and pinned in 10 the other end thereof is a short section 13, which is secured into a coupling 14, pinned upon the motor drive shaft 5.

Secured upon the shaft 9, as shown in Figs. 7 and 9, is a disk 15, and pivoted 15 thereon are two arms 16, mounted on pintles 17. At the opposite ends of each of said arms 16, from the pintles 17, tension springs 18, are connected between said arms. Said arms are adapted to be thrown outwardly 20 by centrifugal force, thereby thrusting a serrated or roughened clutch surface 19, into contact with the inner periphery of a clutch wheel 20, which is secured upon a sleeve 21, journaled on the shaft 9, said tension springs 25 18, serving to resist the outward movement of said arms.

Formed integral with the sleeve 21, is a pinion 22. Journaled upon a stud shaft secured in an extension of the frame casing 7, 30 is a large gear 23, meshing with the pinion 22, and rigidly associated with said gear 23, is a small pinion 24. Said pinion 24, meshes with a large gear 25, which is secured upon a shaft 26, journaled horizontally in the lower 35 portion of the casing 7. Journaled upon the shaft 26, are a pair of pinions 27 and 28, respectively, each meshing with a large bevel gear 29, which is secured upon a shaft 30, extending through a bearing 31, in the casing 7, into the tub 2, of the washing machine, 40 for connection to the clothes drum (not shown) therein. Feathered upon the shaft 26, between the pinions 27 and 28, is a slideable jaw clutch member 32, adapted to engage with either of the complementary jaws provided on the extensions of the pinions 27 and 28, to lock the same to the drive shaft 26, and thereby drive the bevel gear 29. When the jaw clutch member 32, is in the 45 intermediate or neutral position shown in Fig. 4, it is out of engagement with both of the pinions 27 and 28, and no drive is imparted to the gear 29, for operation of the clothes drum.

50 The automatic mechanism for shifting the jaw clutch member 32, first into engagement with the pinion 27, and then into engagement with the pinion 28, to reverse the drive to the clothes drum is the same as that shown in my copending application for patent for "clutch shifting mechanism", filed September 13th, 1915, issued April 8, 1919, Patent No. 1,299,925, and hence the details of construction will not be entered into here since 55 they form no part of the present invention.

The shifting arm or lever for the jaw clutch member 32, is slightly different from that shown in the application above mentioned, and in the present instance, is denoted by the reference numeral 33. Said arm is 70 provided with an extension 34, which fits around the slideable member 32, and the end of the yoke is provided with a recess to receive a spring impelled pin 35, engaged therewith to hold said shifting arm 33, in 75 neutral position. Said pin 35, extends into a bearing provided therefor in the cover plate 8, and at its outer end is provided with a handle or crank 36, with a cam projection or extension 37, adapted to co-act with an inclined cam portion 38, of the cover plate 8, so that by a rotational adjustment of the handle 36, the portion 37, rides upwardly on the cam portion 38, thereby retracting the pin 35, against the stress of its spring and 85 releasing the arm 33.

Secured upon the outer end of the shaft 26, is a bevel pinion 39, meshing with a bevel pinion 40, which is secured on the lower end of a shaft 41, extending upwardly within 90 the casing. Said shaft 41, extends into an adjustable casing or housing 42, pivotally mounted upon the upper end of the casing 7, and supported at one side of the housing upon a frame bracket or arm 43, is a power 95 driven wringer 44. Said housing 42, is limited in its different adjusted positions upon the upper end of the casing 7, by means of a lever 45, pivoted thereon with the lower end of the lever adapted to engage in notches 100 in the top of the casing 7, as shown in Fig. 4, to hold said casing 42, and wringer 44, in different adjusted positions. Said lever 45, is normally held in engaging position by a spring impelled detent 46, mounted in the 105 side wall of the adjustable casing 42. Feathered upon the upper end of the shaft 41, within the casing 42, is a slideable jaw clutch element 47, adapted to interlock with either one of two bevel pinions or gears 48 and 49, 110 respectively, journaled upon said shaft 41, within the casing 42. Each of said bevel pinions 48 and 49, meshes with a bevel gear 50, secured upon a shaft 51, journaled through the side wall of the casing or housing 42, and to which one of the wringer roll shafts 52, is connected by means of a coupling 53. When the clutch member 47, is in either one of its engaged positions, the periphery thereof is so disposed as to prevent 115 inward movement of the spring detent 46, whereby the lever 45, is held against movement into a releasing or unlatching position so that it is obvious that no adjustments of the housing 42, can be made while the 120 wringer is under the operation of the power drive.

Journaled through the side wall of the housing 42, is a shaft 54, as shown in Fig. 8, provided with an actuating handle 55, on 130

the outer end thereof, and on its inner end provided with an eccentric pin 56, on which is journaled a block 57, for engagement with the central peripheral groove of the slidable clutch member 47. Adjustments of the handle 55, serve to shift said clutch member 47, into engagement with either one of the pinions 48 and 49, or into a neutral position therebetween when the lever 55, is in the upper right position shown in Fig. 8. A spring 50
5 detent 58, is provided mounted in an extension on the housing 42, to co-act with the lower end of the lever 55, as shown in Fig. 8, to hold the same in neutral position.

15 The operation is as follows:

The drive for the washing machine is received from the motor 4, through the shaft assembly 5-12-9, to disk wheel 15, and through the centrifugally actuated friction 20 arms 16, to the clutch wheel 20. The pinion 22, rigidly associated with the clutch wheel 20, in turn drives the large gear 23, which, with the pinion 24, rigidly associated therewith drives the large gear 25, on the shaft 25 26. The shaft 26, serves to transmit a drive through the reversing gear mechanism to the clothes drum within the tub 2, and also to the upright wringer shaft 41. When the lever 36, is moved into the position shown in Fig. 5, the pin 35, engages with the yoke arm 34, of the shifting lever 33, holding the same in neutral position and preventing engagement of the slidable clutch member 32, with either of the pinions 27 and 28, so that 35 no drive is imparted to the clothes drum.

The upright wringer shaft 41, is driven continuously with the shaft 26, and the wringer may be driven at the option of the operator by swinging the clutch lever 55, in one position or the other to drive the wringer in either direction. The wringer mechanism and clothes drum mechanism may be operated independently of one another from the continuously driven shaft 26. In the 40 event of the wringer mechanism or clothes 45

drum mechanism becoming jammed during operation thereof, the mechanisms will not be damaged for the reason that the clutch mechanism 15-20, will slip when over-loaded to this extent. 50

I am aware that various details of construction may be varied through a wide range without departing from the principles of this invention, and I therefore do not purpose limiting the patent granted otherwise than necessitated by the prior art. 55

I claim as my invention:

1. Transmission mechanism for washing machines comprising a casing adapted to be attached on the side of a washing machine, a driven shaft adapted to drive a plurality of mechanisms supported in said casing, a motor driven shaft also supported in said casing, and having a pinion loosely mounted thereon, a clutch drum secured to 60 said pinion, centrifugal clutch mechanism connecting said drum and motor driven shaft, an intermediate shaft having a gear meshing with said pinion and intermeshing gears on said intermediate shaft and said 65 first mentioned shaft. *

2. Transmission mechanism for washing machines comprising a casing adapted to be attached on the side of a washing machine and having a plurality of shaft bearing portions therein, a plurality of shafts supported by said bearing portions, intermeshing gears mounted on said shafts, one of said 70 gears being rotatably mounted upon one of said shafts and having an extension, a clutch 75 member secured on said extension, and centrifugal clutch mechanism connecting said last mentioned shaft and said clutch member.

In testimony whereof I have hereunto subscribed my name in the presence of two sub- 80 scribing witnesses. 85

HAROLD W. EDEN.
